DESIGN FOR A COMBINATION SAUCEPAN

Jerome A. Wagner, Sidney, Ohio, assignor to The Wagner Manufacturing Company, Sidney, Ohio,
a corporation of Ohio

Application July 22, 1935, Serial No. 57,778

Term of patent 7 years

To all whom it may concern:

Be it known that I, Jerome A. Wagner, a citizen of the United States, residing in the city of Sidney, in the county of Shelby and State of Ohio,
have invented a new, original, and ornamental Design for a Combination Sauce Pan, of which the following is a specification, reference being had to the accompanying drawing, forming part thereof.

The figure is a perspective view of a combination sauce pan, showing my new design.

I claim:

The ornamental design for a combination sauce
pan, as shown.

JEROME A. WAGNER.
